(57) **CLAIM**

The ornamental design for a V-engine inboard-intake manifold cover, as shown and described.

DESCRIPTION

FIG. 1 is a top view of an ornamental design for a V-engine inboard-intake manifold cover, according to the invention.

FIG. 2 is a bottom view of the manifold cover of FIG. 1.

FIG. 3 is a front view of the manifold cover of FIG. 1.

FIG. 4 is a rear view of the manifold cover of FIG. 1.

FIG. 5 is a right view of the manifold cover of FIG. 1.

FIG. 6 is a left view of the manifold cover of FIG. 1.

FIG. 7 is a first perspective view of the manifold cover of FIG. 1; and,

FIG. 8 is a second perspective view of the manifold cover of FIG. 1.

The broken lines form no part of the claimed design.
